UNITED STATES PATENT OFFICE.

WILLIAM L. MARTIN, OF BOYNE CITY, MICHIGAN.

SHIELD FOR THE PROTECTION OF SHIPS.

1,311,002.

Specification of Letters Patent. Patented July 22, 1919.

Application filed October 19, 1918. Serial No. 258,771.

To all whom it may concern:

Be it known that I, WILLIAM L. MARTIN, a citizen of the United States, residing at Boyne City, in the county of Charlevoix and 5 State of Michigan, have invented new and useful Improvements in Shields for the Protection of Ships, of which the following is a specification.

My invention relates to a device especially 10 designed as a shield or a guard for the protection of ships and other boats or vessels from destruction by torpedoes fired from submarines.

The main object of this invention is to 15 provide simple, practical and efficient means suitably secured to the sides of a ship or other boat, in order to arrest a torpedo, and prevent its contact with the body or hull of the vessel.

Another object of the invention is to provide a floating boom with a protecting shield 20 secured thereto, said shield depending a sufficient distance below the boom and from the sides of a ship to properly protect the hull 25 of the ship, and built in sections suitably coupled together and secured to the side of the ship by means of a bracket or arms hinged to the top of the boom, whereby the shield is held or retained at a suitable distance 30 from the side of the ship to prevent its pounding or contact with the sides thereof, the whole adapted to be towed by a line or cable suitably secured to the bow of the ship.

A further object of my invention is to 35 furnish a novel means of protecting ships from destruction by torpedoes, by utilization of a float with a shield secured to and suspended from said float, designed to be coupled together in a string or train, suitably 40 attached to the side of the ship with an arm or bracket and drawn or towed by a cable, adapted to be used to advantage in the shorter runs in the danger zone, and it may be used in longer or more extended runs 45 outside of the danger zone.

The foregoing and such other objects as 50 may appear from the ensuing description are attained by the combination, construction and arrangement of the parts hereinafter more fully described and illustrated in the accompanying drawings, and particularly pointed out in the claims appended hereto, it being understood that slight changes in the precise form and construction 55 may be resorted to without departing

from the spirit or sacrificing any of the advantages of the invention.

In the accompanying drawings which form a part of the specification it will be seen that:—

Figure 1, is a side elevation of the device 60 embodying my invention, showing it applied to the side of a ship or other vessel.

Fig. 2, is a transverse sectional view of the device showing it attached to one side of 65 the hull of the ship or vessel.

Fig. 3, is a side elevation of one of the shields secured to the float and detached from the ship.

Fig. 4, is a vertical section of the device 70 shown in Fig. 3, and

Fig. 5, is a detail plan view of the float with the bracket or arm hinged thereto.

Fig. 6, is a vertical section showing the 75 means of attaching the cable wire to the device.

Similar characters of reference are employed to designate corresponding parts throughout the several figures of the drawings.

In carrying out my invention the device is 80 shown as applied to only one side of the hull of a ship, but it will be understood that it may be secured to either or both sides of the hull.

A designates the hull of a ship or other vessel, and 1 the bracket arms pivotally and removably secured in any suitable manner to said hull above the water line, the inner end 2, of each arm being preferably secured 90 to an eye bolt 3, firmly secured to the hull so that the bracket may be swung in an upward and inward direction when desired,

the outer ends 4, of the bracket arms being suitably hinged at 5 to a hollow metallic 95 float 6 of any suitable or desirable shape, preferably somewhat spherical, and made of sheet steel, which if desired, may be strengthened by cross rods or a light frame secured within the float. The top portion 100 of the float is provided with an angle iron 7, for strengthening and stiffening said portion, and to the bottom portion 8 of the float a shield 9 is suitably secured and suspended therefrom to a sufficient distance below the 105 water line to protect the hull from contact with submarine torpedoes and preferably consists of a series of steel bars or plates 10, or wood slats covered with steel, suitably secured to each other and to the bottom por-

tion of the float by flexible wire cables 11, thereby forming a flexible shield, and the front and rear end portion of each side of each float is flattened at 12 for the purpose 5 of reducing their resistance while being towed along with the ship.

It will be understood that these shields are built in sections, each provided with and secured to a float, and are coupled together 10 in any suitable manner, in a line or like a train of cars from the bow to the stern of the ship, and to the foremost float the front end portion 13, is provided with an angle iron 14, adapted to strengthen and stiffen 15 the same, to which angle iron 14 is suitably secured a towing cable 15, the latter being secured in any suitable manner to the bow of the ship, whereby the series of shields coupled together may be readily towed along 20 with the movement of the ship.

The wire cable 11, is secured to the series of plates or bars 10 by means of staples or such like equivalent 16.

It will be readily perceived that the 25 bracket arms may be provided with means secured thereto whereby the said arms may be swung upward and inward so that when desired the shields may be raised and adjusted to rest against the side of the ship, substantially above the water line.

Having described my invention, what I claim and desire to secure by Letters-Patent is:

1. A device of the character described 35 comprising a plurality of bracket arms, each of said bracket arms being pivotally secured intermediate its length to the hull of a ship, metallic floats provided with a reinforced upper portion to which each end of 40 each bracket arm is hingedly secured, a shield composed of a series of horizontally arranged slats flexibly secured together and suspended from the bottom portion of each float, and a towing cable secured to the front 45 end of the foremost float and to the bow of the ship.

2. A device of the character described comprising a plurality of bracket arms, each of said bracket arms being pivotally 50 secured intermediate its length to the hull of

a ship, a plurality of hollow metallic floats each having a reinforced upper portion to which each end of each bracket arm is hingedly secured, a shield composed of a series of horizontally disposed slats suspended 55 from the bottom portion of each float, a plurality of perpendicularly disposed flexible means for securing the said slats together, and a towing cable secured to the front end of the foremost float and the bow of the ship. 60

3. A device of the character described comprising a plurality of bracket arms, each of said bracket arms being pivotally secured intermediate its length to the hull of the ship, a plurality of hollow metallic floats, 65 each float having an angle iron reinforcement at its upper portion to which each end of each bracket arm is hingedly connected, a shield composed of a series of horizontally disposed slats suspended from the bottom 70 of each float, a plurality of perpendicularly disposed flexible wire cables for flexibly securing said slats together, and a towing cable secured to the front end of the foremost float and the bow of the ship. 75

4. A device of the character described comprising a plurality of bracket arms, each of said bracket arms being pivotally secured intermediate its length to the hull of a ship, a plurality of metallic floats having 80 an angle iron reinforcement at the upper portion to which each end of each bracket arm is hingedly connected, each float having a flattened portion at each end thereof, a shield composed of a series of horizontally 85 disposed wooden slats covered with steel suspended from the bottom of each float, a plurality of perpendicularly disposed flexible wire cables connecting each of the slats together, and a towing cable connected to 90 the front end of the foremost float and the bow of the ship.

In testimony whereof I have hereunto set my hand in presence of two subscribing witnesses.

WILLIAM L. MARTIN.
